UNITED STATES PATENT OFFICE.

ED WILSON FARNHAM, OF CHICAGO, ILLINOIS.

ELECTRIC RAILWAY.

SPECIFICATION forming part of Letters Patent No. 696,023, dated March 25, 1902.

Application filed September 23, 1901. Serial No. 76,289. (No model.)

To all whom it may concern:

Be it known that I, ED WILSON FARNHAM, a citizen of the United States, residing at Chicago, in the county of Cook and State of Illinois, have invented certain new and useful Improvements in Electric Railways, of which the following is a specification.

This invention relates to those systems of electric railways wherein the third or contact rail is made up of a series of insulated sections, which sections are charged one after another as the car passes over them and places each by the movement of the section or otherwise in electric communication with the conductor main or cable that supplies current to the system.

An object of this invention is the improvement in the construction of electric-railway systems of the kind mentioned.

20 A further object lies in the improved means for suspending the movable sections of the contact-rail.

A further object consists in the improved means for supporting the fixed or guide sections of the contact-rail.

In the accompanying drawings, Figure 1 is a diagrammatic representation of a portion of an electric railway embodying my invention. Fig. 2 is a similar view showing the arrangement of the contact-rail for passing a street-crossing when said contact-rail is elevated above the ground. Fig. 3 is a side elevation of a portion of a movable contact-rail and the switch actuated by the movement of the rail, 35 also showing the contact-shoe and the guide-rail adjacent to the contact-rail. Fig. 4 is a top plan view of the means for supporting the fixed and the movable rails within the wooden casing extending beside the track when the 40 contact-rail is to be placed above the surface, portions of the casing intermediate the supporting-standards being broken away to attain greater clearness. Fig. 5 is a longitudinal vertical section on dotted line 55 of Fig. 45 4. Fig. 6 is a top plan view of the means for supporting the sections of the movable rail. Fig. 7 is a transverse vertical section on dotted line 77 of Fig. 6. Fig. 8 is a side elevation of the pivotal link for suspending the movable 50 rail-section. Fig. 9 is a view of an insulating-block, two of which are employed in supporting the hanger for the pivotal link. Fig.

10 is a fragmental view showing a guide for directing the shoe upon a movable section of the contact-rail. Such a guide is necessary 55 at street-crossings, as shown in the diagrammatic view Fig. 2. Fig. 11 is a top plan view of the contact-shoe. Fig. 12 is a view, partly in section, illustrating the insulating-guide for a movable section of the contact-rail. Fig. 60 13 is a top plan view of said guide. Fig. 14 is a view similar to Fig. 12, illustrating one of the insulated supporting-blocks for supporting the fixed guide-rail.

Like letters of reference indicate corresponding parts throughout the several views.

This invention is adapted to be placed either above the surface of the ground beside the road-bed or in a suitable conduit beside the track or between the rails thereof.

A represents an upright supporting-standard secured in any suitable manner to the ties of the road-bed or within the bottom of a conduit. At its upper end it carries a continuous wooden casing A', extending parallel with the track. Within this casing and placed opposite to each supporting-standard A and secured thereto by means of the bolts A² is a bracket A³, having upon its upper surface the groove or depression A⁴ for receiving the conductor-main A⁵. At opposite sides this bracket is cut away for a short distance at A⁶ to provide recesses for receiving the insulating-blocks A⁷, of wood or other suitable material, which insulating-blocks 75 are provided with the inwardly-extending ears A⁸ for engaging the end walls of the bracket A³ to hold the insulating-blocks A⁷ in place. The tops of the blocks A⁷ are provided with the recesses A⁹ and with the holes A¹⁰, extending through the blocks from the middle portion of said recesses. These recesses are adapted to receive the ends of the supporting-hanger B, one of which is placed in each of the brackets A³. The hanger B 80 comprises a top plate B', rounded at its ends to fit within the recesses A⁹ of the insulating-blocks A⁷ and having the holes B², adapted to coincide with the holes A¹⁰, extending through said insulating-blocks to receive the securing-bolts B³. The plate B' is provided with a transverse groove B⁴ to provide a resting-place for the conductor-main A⁵. Extending downward from the under side of the 85 90 95 100

top plate B' are two ears B⁵, perforated to receive a hardened triangular pin B⁶.

Links C, composed of the two side members C', are adapted to be supported upon 5 said triangular pin B⁶ and at their lower ends are provided with openings C² to receive the end of a pin passing through the movable section of the contact-rail. The arms C' are secured together at their middle portions by a 10 rivet C³, extending through suitable openings in said arms. The rivet C³ also holds two cap-plates C⁴ in frictional contact with the outer sides or arms C', the cap-plate under the head of the rivet C³ being capable of 15 an oscillatory movement upon said rivet, so it may be turned to one side, as shown in Fig. 8, to permit of the insertion or withdrawal of the pivotal pin extending transversely through the contact-rail and upon which pin 20 said rail is supported.

D is a section of the contact-rail.

D' is the pivotal pin extending transversely through a suitable opening in said rail, the outer ends of which pin lie within the openings C² in the lower ends of the sides C' of the 25 links C. The rail D is supported by two or more of the links C. A contact point or finger D² is fixed to one side of each section D of the contact-rail and is adapted to act as one 30 part of a switch (to be later herein described) for making electric connection between the section D and the conductor-main A⁵.

E is a contact-shoe carried by the car. It is composed of two contact-blocks E', their 35 adjacent faces being beveled at their ends and covered with the insulated metallic strips E², the insulating-strip on one of said shoes providing a yielding contact with the contact-rail by means of the backing-springs E³ of said 40 shoe. The contact-blocks are fixed upon the guide-rods E⁴, supported by the car.

F is a two-point switch secured to the casing A' in electric connection with the conductor-main A⁵. The contact-point D² extends 45 upward and is adapted to be placed in contact with either one of the two contact-points of the switch by the movement of the rail D upon its link-supports. When the contact-point D² is in contact with either one of the 50 points of the switch, the movable section of the rail carrying the contact-point is charged with electric current.

F' is an insulated guide-block carried by the bracket A³ and bifurcated at its lower end 55 to receive the top of the rail D to guide said rail in its longitudinal pivotal movement. This guide-block is insulated by the split wooden bushing F² and is held in position by the clamp F³, secured to the side of the bracket 60 A³ by means of suitable bolts.

G is a stationary guide-rail. It is suspended within the casing A' in line with the movable sections D of the contact-rail in any suitable manner. Its purpose is to hold the two members of the contact-shoe C separated, so that 65 they shall pass from one movable section D to another without shock or jar. The station-

ary guide-rail is supported by means of the specially-constructed brackets illustrated in Figs. 4 and 5, having insulated supporting-blocks similar to those F'.

G' is the supporting-block for the stationary guide-rail, G² the insulating-bushing, and G³ the bracket for holding the block G' in position. The bracket G³ is adapted to extend 75 from one side of the casing A' to the other side thereof, and the insulating-bushing and the guide-block are frictionally held in place by the cap G⁴ and the bolts G⁵. The guide-rails are secured between the lower bifurcated 80 ends of the guide-block by rivets G⁶, passing through suitable openings in said rail and said guide-blocks.

H represents two guide-arms for directing the contact-shoe upon a short section of guide-rail G when said shoe has left the guide-rail to pass a street-crossing, as shown in the diagrammatic view Fig. 2.

H' represents bolts, and H² represents sleeves for securing the guide-arms H in position within the casing A'.

In operation the conductor-rails comprising longitudinally-movable sections D of the contact-rail and fixed sections G of the guide-rail are placed alternately in longitudinal series 95 and supported beside the track, as represented in Fig. 3, or within a suitable conduit below the surface, and the two-point switches F are placed in electric communication with the conductor-main A⁵. The frictional contact 100 between the contact-blocks E' of the contact-shoe E, grasping between them the sections D of the contact-rail as the car moves forward upon the track, is sufficient to move said sections longitudinally upon their pivotal links 105 C, moving the contact-point D² into contact with one of the two points of the switch F, thereby placing the section D of the contact-rail in electric communication with the conductor-main A⁵ and charging said section with 110 the electric current. The contact-shoe is in electric communication with the translating mechanism (not shown) and the current therefore is conducted to the motor to drive the car.

The V-shape pivotal pins B⁶ and D' make knife-blade antifriction-bearings for the support of the movable rail-sections D and permit of their easy movement.

I claim as my invention—

1. In an electric railway, in combination, a conductor-main; a series of guide-rails; means for supporting said guide-rails; a series of standards; a bracket secured to each of said standards; a pivotal link suspended in each 125 of said brackets; and a moving contact-rail having a pivotal connection with the lower end of said pivotal link.

2. In an electric railway, in combination, a conductor-main; a contact-rail comprising a 130 number of independent sections, alternately fixed and movable; a series of standards; a bracket for each of said standards; a hanger supported in certain of said brackets; and a

pivotall link suspended in said hanger and having a pivotal connection with the movable section of the contact-rail.

5. In a means for suspending a contact-rail for electric railways, in combination, a standard; a bracket secured thereto; a pivotal link suspended in said bracket; and a contact-rail having a pivotal connection with the lower end of said pivotal link.
10. 4. In a means for suspending a contact-rail for electric railways, in combination, a standard; a bracket secured thereto; a hanger in said bracket; a pivot in said hanger; a link suspended upon said pivot; and a contact-rail pivotally suspended in the lower end of said pivotal link.

5. In a means for suspending a contact-rail for electric railways, in combination, a standard; a bracket secured thereto; insulating-blocks in said bracket; a hanger mounted upon said insulating-blocks; a pivot in said hanger; a link suspended upon said pivot; and a contact-rail having a pivotal connection with the lower end of said pivotal link.

25. 6. In a means for suspending a contact-rail for electric railways, in combination, a standard; a bracket secured thereto; two insulating-blocks in said bracket; a hanger mounted upon said insulating-blocks; a knife-edge pivot in said hanger; a link suspended upon the knife-edge of said pivot, having an opening in each of its ends; and a contact-rail having a knife-edge pivot adapted to lie within the opening in the lower end of said pivotal link.

35. 7. In a means for suspending a contact-rail for electric railways, in combination, a standard; a bracket secured thereto; insulating-blocks in said bracket; a hanger mounted upon said insulating-blocks, said hanger having two depending perforated ears; a knife-edge pivot supported in the perforations of said ears; a link provided with perforations in its opposite ends, suspended upon said

knife-edge pivot; a contact-rail having a 45 knife-edge pivot adapted to lie within the opening in the lower end of said pivotal link; and a cap-plate secured to the link for holding said rail-pivot in position.

8. In a means for suspending a contact-rail 50 for electric railways, in combination, a standard; a bracket secured thereto, said bracket being provided with depressions at its ends to receive the conductor-main; insulating-blocks in said bracket; a hanger mounted 55 upon said insulating-blocks, said hanger having a transverse depression for receiving the conductor-main, also having two depending perforated ears; a knife-edge pivot supported in the perforations of said ears; a two-part link suspended upon said knife-edge pivot, said link being provided with openings at its upper and its lower ends; cap-plates secured to the sides of said link, for covering the openings at the lower end thereof; and a 60 contact-rail having a knife-edge pivot adapted to lie in the lower opening of said pivotal link.

9. In a means for suspending a guide-rail 70 for electric railways, in combination, a standard; a bracket secured thereto; an insulating-bushing; a supporting-block within said bushing, bifurcated in its lower end; and means for securing the contact-rail between the bifurcated ends of said block.

10. In a means for suspending a guide-rail 75 for electric railways, in combination, a standard; a bracket secured thereto; a pivotal link suspended in said bracket; a contact-rail having a pivotal connection with the lower end 80 of said pivotal link; a guide-block bifurcated at its lower end; an insulating-bushing for said guide-block; and means for securing said guide-block and bushing to said bracket.

ED WILSON FARNHAM.
